UNITED STATES PATENT OFFICE.

GEORGE M. WALLACE, OF RENSSELAER, NEW YORK, ASSIGNOR TO F. C. HUYCK & SONS,
OF RENSSELAER, NEW YORK, A CORPORATION OF NEW YORK.

MEANS FOR WATERMARKING PAPER.

Application filed April 7, 1922. Serial No. 550,452.

To all whom it may concern:

Be it known that I, GEORGE M. WALLACE, a citizen of the United States, residing at Rensselaer, in the county of Rensselaer and 5 State of New York, have invented certain new and useful Improvements in Means for Watermarking Paper; and I do hereby declare the following to be a full, clear, and exact description of the invention, such as 10 will enable others skilled in the art to which it appertains to make and use the same.

The invention relates to means for watermarking paper during its manufacture.

The object of the invention is to provide 15 means for economically and efficiently producing any desired water mark design whether of a simple or complex nature without interfering with the proper passage of the paper stock through the machine and 20 without danger of injuring or weakening either the web or its cellulose fibres.

To this end the invention comprises a 25 water marking roller having a periphery of heavily felted woolen fabric with a raised marking design thereon which, for the best results, should also be of wool. A marking roller of this character is peculiarly adapted for producing a well defined mark or design 30 in the paper web while in a damp, soft condition without injury to the web or to the cellulose fibres and without disturbance of the fibres except at the points where the design should appear. This is due to the fact that firmly woven and felted wool fabric has 35 the characteristic property of permitting the soft and damp web of paper stock which has been pressed against it to separate therefrom without surface tension or friction and without any tendency to injure or distort 40 the web. The felt periphery of the marking roll may, therefore, press firmly upon the moist paper web without in any wise interfering with the passage of the paper and the raised woolen design thereon may spread 45 and thin the web of paper without injuring the fibres or weakening the web. A well defined clear cut water mark design is thus impressed upon the paper without any tendency to disrupt or injure the cellulose fibres 50 or the web and without interfering with the passage of the paper web through the paper making machine.

The felt covering may be applied and secured to the periphery of the roll in any

suitable manner and the water mark design 55 may be formed on the felt in any suitable manner. It is preferred, however, to form the design upon a strip of firmly woven and heavily felted wool fabric and to wind the strip spirally on the roll with its edges 60 closely abutting so that when in place on the roll the strip presents a smooth unbroken surface throughout that part of the periphery which runs in engagement with the paper stock. The water mark design may 65 be conveniently and economically formed on a strip of this character by a stitching or embroidering machine constructed to form a suitably raised seam on the surface of the 70 felt strip. The desired design may be readily laid out on the felt strip so that it may be followed by the operator of the stitching or embroidering machine and so that it will be properly located on the surface of the roll when the strip is wound 75 and secured thereon.

A preferred construction of roll embodying the invention is shown in the accompanying drawings in which the figure shows 80 a water marking roll embodying the invention in its preferred form.

As shown in the drawings the water mark design consists of a series of groups of letters and scrolls 2 arranged in line lengthwise of the roll. Each group of letters and scrolls may be considered as a component part of a complete design and the design indicated may be considered as merely symbolic of a more or less complex design, the 85 component parts of which have a predetermined relation to each other upon the periphery of the roll. The periphery of the roll consists of a strip 4 of woven and heavily felted woolen fabric which is wound 90 spirally upon the cylindrical body 6 of the roll with its edges closely abutting so that the strip presents a smooth unbroken surface throughout the periphery of the roll. The strip may be secured to the roll in any 95 suitable manner as by fastening indicated at 8. The groups of letters 2 forming the component parts of the water mark design are so arranged and spaced on the strip that they will be brought into the desired relation to each other on the periphery of the 100 roll when the strip is wound spirally thereon with its edges closely abutting. The design 105 is laid out on the strip and then formed by a

stitching machine which is threaded with a wool thread and sews a raised seam on the surface of the felt strip following the lines of the design previously laid out thereon. 5 In this manner any simple or complex design may be conveniently and economically formed on the peripheral covering for the marking roll while it is in flat strip form and the component parts of the complete 10 design with which the periphery of the roll is to be provided may be so arranged on the strip that they will be brought into the desired relation to each other on the surface of the roll when the strip is wound spirally 15 thereon.

The felt covered roll may be of any suitable length and diameter to meet the conditions under which it is to be utilized. The roll may be arranged at any convenient or 20 desired place to act on the paper after it leaves the Fourdrinier wires and before it enters the heated drying cylinders so that it will act upon the cellulose web while it is in a soft and damp condition. The requisite 25 pressure between the roll and the surface of the paper may also be secured in any suitable manner.

While it is preferred to utilize the construction shown and described it will be 30 understood that this is not essential and may be varied or modified as found desirable without departing from the broader features of the invention.

What is claimed is:

35 1. A roll for water marking paper during its manufacture provided with a periphery of felted woolen fabric having on its surface a raised seam of stitches forming a water marking design.

40 2. A roll for water marking paper during its manufacture provided with a periphery of felted woolen fabric having on its sur-

face a raised seam of woolen stitching forming a water marking design.

3. A roll for water marking paper during 45 its manufacture, the periphery of which consists of a strip of woven and felted woolen fabric wound spirally thereon with closely abutting edges and having on its surface a raised marking design.

4. A roll for water marking paper during 50 its manufacture, the periphery of which consists of a strip of woven and felted woolen fabric wound spirally thereon with closely abutting edges and having on its surface a raised marking design also of wool.

5. A roll for water marking paper during 55 its manufacture, the periphery of which consists of a strip of woven felted woolen fabric wound spirally thereon with closely abutting edges and having on its surface raised stitching forming a water marking design.

6. A peripheral covering for a roll for 60 water marking paper during its manufacture consisting of a strip of woven and felted woolen fabric having on its surface a raised water marking design, the component parts of which are arranged along the strip to bring them into proper relation to each other on the surface of the roll when 65 the strip is wound spirally thereon with edges abutting.

7. A peripheral covering for a roll for 70 water marking paper during its manufacture consisting of a strip of woven and felted 75 woolen fabric having on its surface a raised woolen water marking design, the component parts of which are arranged along the strip to bring them into proper relation to each other on the surface of the roll when 80 the strip is wound spirally thereon with edges abutting.

GEORGE M. WALLACE.
